UNITED STATES PATENT OFFICE.

HUGH R. WEAVER, OF PITTSBURGH, PENNSYLVANIA.

IRONING-BOARD.

1,369,861.

Specification of Letters Patent.

Patented Mar. 1, 1921.

Application filed November 8, 1920. Serial No. 422,500.

To all whom it may concern:

Be it known that I, HUGH R. WEAVER, residing at Pittsburgh, in the county of Allegheny and State of Pennsylvania, a citizen of the United States, have invented or discovered certain new and useful Improvements in Ironing-Boards, of which improvements the following is a specification.

The invention described herein relates to certain improvements in ironing-boards and has for its object a construction whereby a support for one end of the boards, as the edge of a table-top or a shelf is firmly gripped between the end of the board and a pivotally mounted member or lever, which is adapted to form a portion of the support for the opposite end of the board, the other member of such support being formed by a strut or leg pivotally connected to the board and adapted to be adjusted along the lever as the board is being moved to the desired horizontal position. The invention is hereinafter more fully described and claimed.

In the accompanying drawing forming a part of this specification, Figure 1 is an elevation showing the ironing-board in operative position; Figs. 2 and 3 are transverse sections; and Fig. 4 is a view on an enlarged scale showing the manner of connecting the supporting strut and catch to the sleeve on the lever.

In the practice of the invention, a U-shaped clip 1 is secured to the underside of the board a short distance from one end thereof, and a section of pipe 3 is pivotally supported between the legs of the clip by a pin 4 passing through the legs of the clip and the pipe section. This pipe section is so mounted on the board that when the end of the latter is placed on a table top indicated at 5 and the free or outer end of the pipe allowed to drop, the table edge will be firmly gripped between the board and the portion of the pipe at the left of its pivotal point. The lever is made of such a length that when the board is in the desired position the end of the lever will rest on the floor, and in order that the short end of the lever may not bear on the underside of the table 5 before the opposite end of the lever rests on the floor, the legs of the clips 1 have a plurality of holes for the pivot pin so that the position of the lever in the clip

may be changed to suit different thicknesses of the element 5. A strut 6 is pivotally connected to the underside of the board at a point intermediate the ends of the board and has its opposite end pivotally connected to a sleeve 7 slidably mounted on the lever. When the lever is dropped, the board being supported in a horizontal position the sleeve will slide along the lever and is locked to the lever in the position it reaches when the end of the lever rests on the floor.

It is preferred that the strut 6 should be made of a section of pipe and that its upper end should project between the sides of a U-shaped strip of metal 8 to which the strut is pivotally connected by a pin 9. It is preferred that a plurality of holes should be made through the sides of the strip 8 for the reception of the pivotal pin 9, thereby permitting of the shifting of the point of connection of the strut with the board. The lower end of the pipe section or strut should be slotted for the reception of the end of the trigger 10, it being held in place by a pin passing through ears 11 on the sleeve 7, the strut and the trigger. The trigger is provided with a pin 12 adapted to engage holes 13 in the upper side of the lever.

I claim herein as my invention:

1. An ironing board having in combination a lever formed of a section of pipe pivotally connected to the underside of the board, a strut formed of a section of pipe and having its upper end pivotally connected to the board, a sleeve slidably mounted on the lever and a trigger adapted to engage the lever, the sleeve and trigger being pivotally connected to the lower end of the strut.

2. An ironing board having in combination therewith a U-shaped clip secured to the underside of the board, a lever formed by a section of pipe adjustably pivoted between the legs of the clip, a strut formed of a section of pipe, an adjustable pivotal support for the strut connected to the underside of the board intermediate its ends, a sleeve movably mounted on the lever, and a catch adapted to engage the lever, the sleeve and catch being pivotally connected to the strut.

In testimony whereof, I have hereunto set my hand.

HUGH R. WEAVER.
